CONVERSION OF NAPHTHENES TO HIGHER AROMATICS

Richard W. Blue and Vernon C. F. Holm, Bartlesville, Okla., assignors to Phillips Petroleum Company, a corporation of Delaware

Application July 11, 1952, Serial No. 298,402

14 Claims. (Cl. 260—668)

This invention relates to a process for the conversion of naphthenes to aromatics containing a greater number of carbon atoms per molecule than the original naphthene. In a more specific aspect this invention relates to a process for the production of aromatic hydrocarbons from naphthenic and olefinic hydrocarbons by a hydrogen transfer process whereby the aromatics are recovered by distillation. In another specific aspect this invention relates to a method for producing 1,2,4-trimethyl benzene.

Naphthenic straight-run gasoline fractions, have in general, relatively poor anti-knock properties, and are therefore not well suited for blending in gasolines in which a high octane rating is desired. Aromatic hydrocarbons, however, impart high octane rating to motor fuels and are in great demand. The demand for aromatic hydrocarbons for use in chemical industries is so great that it has become impractical to add aromatics to motor fuels solely for their octane rating characteristics. Thus a process for producing aromatics from naphthenes is very desirable.

Each of the following objects will be attained by the aspects of this invention.

It is an object of this invention to provide a process for the production of alkyl aromatics from a mixture of olefins and naphthenes.

Another object is to provide a process for improving the octane rating of a motor fuel containing olefins and naphthenes.

Another object is to provide a process for converting naphthenes into aromatics having a greater number of carbon atoms per molecule than the original naphthene.

Another object is to provide a method for the production of aromatics wherein the aromatics produced can be removed from the reactants by distillation.

Another object is to provide a method for producing 1,2,4-trimethyl benzene.

Another object is to provide a novel hydrogen transfer process.

Other objects and advantages will be apparent to one skilled in the art upon reading this specification and the attached drawing.

We have discovered that a hydrocarbon mixture containing olefins and naphthenes can be subjected to hydrogen transfer reaction conditions in the presence of a catalyst selected from the group consisting of alumina-aluminum fluoride, silica-magnesia, silica-boria, and silica-alumina, and the catalyst bases silica-alumina and silica, activated by oxides of the metals of groups 3-B and 4-B of the periodic table of elements with the result that aromatic hydrocarbons are produced having a greater number of carbon atoms per molecule than contained in the original naphthene and the aromatics can be recovered by distillation.

The metals of groups 3-B and 4-B of the periodic table of elements are those set forth in "Lange's Handbook of Chemistry," 5th edition, 1944, at pages 54 and 55. Therein the metals of group 3-B are stated to be scandium, yttrium, and the rare earth metals and the metals of group

2

4-B are stated to be titanium, zirconium, hafnium and thorium. In the specification and in the claims the metals of groups 3-B and 4-B of the periodic table of elements are the metals as set forth above.

5 In accordance with this invention olefinic hydrocarbons are reacted with naphthenic hydrocarbons in the presence of a catalyst selected from the group consisting of alumina-aluminum fluoride, silica-magnesia, silica-boria, silica-alumina and the catalyst bases silica-alumina and silica, activated by oxides of the metals of groups 3-B and 4-B of the periodic table of elements and under hydrogen transfer conditions so as to produce aromatic hydrocarbons having a higher molecular weight than the naphthene and the aromatic hydrocarbons produced are recovered as the bottom product in a distillation step.

This process provides a novel method for the production of 1,2,4-trimethyl benzene.

Although naphthenes and olefins in general can be used in this process we prefer to use naphthenic hydrocarbons having from 5 to 6 carbon atoms in the ring and olefins having from 3 to 6 carbon atoms. Isobutene is the olefin most generally preferred. When hydrocarbon charge stocks in our preferred range are used in our process the aromatics produced can be separated from the unreacted charge stock by distillation.

10 Naphthenes in our preferred range include methyl cyclopentane, dimethyl cyclopentane, trimethyl cyclopentane, ethyl cyclopentane, methyl-ethyl cyclopentane, isopropyl cyclopentane, n-propyl cyclopentane, cyclohexane, methyl cyclohexane, dimethyl cyclohexane, trimethyl cyclohexane, ethyl cyclohexane, methyl-ethyl cyclohexane, isopropyl cyclohexane, and n-propyl cyclohexane.

15 Olefins in our preferred range include propylene, butenes, isobutene, pentene, isopentenes, hexene and isohexenes.

20 Relatively pure compounds such as methylcyclohexane and isobutene can be treated with this process as desired. This process can also be adapted to the treatment of olefinic hydrocarbon mixtures and naphthenic straight-run gasoline fractions to produce a hydrocarbon mixture containing aromatics. Naphthenic fractions containing at least 20 per cent by volume of naphthenes and olefinic hydrocarbon mixtures containing at least 20 per cent by volume of olefins are preferred charge stocks for this reaction.

25 The ratio of naphthenes to olefins for this reaction is dependent upon the degree of unsaturation of the olefinic charge stock and the available hydrogen in the naphthene. The ratio of naphthenes to olefins in the charge can suitably range from 1:1 to 1:10, with the preferred naphthene to olefin ratio being 1:2 to 1:4.

30 The hydrogen transfer reaction with methylcyclohexane yields a large proportion of aromatic products having a higher boiling point than toluene. Cyclohexane and methyl-cyclopentane give rise to a similar distribution of products.

35 The catalysts which can be used for this hydrogen transfer reaction include silica-alumina, silica-zirconia, silica-alumina-zirconia, silica-boria, silica-scandia, silica-alumina-scandia, silica-yttria, silica-alumina-yttria, silica-praseodymia, silica-alumina-praseodymia, silica-neodymi, silica-alumina-neodymi, silica-illinia, silica-alumina-illinia, silica-samaria, silica-alumina-samaria, silica-europia, silica-alumina-europia, silica-gadolinia, silica-alumina-gadolinia, silica-terbia, silica-alumina-terbia, silica-dysprosia, silica-alumina-dysprosia, silica-holmia, silica-alumina-holmia, silica-erbia, silica-alumina-erbia, silica-thulia, silica-alumina-thulia, silica-ytterbia, silica-alumina-ytterbia, silica-lutecia, silica-alumina-lutecia, silica-titania, silica-alumina-titania, silica-hafnia, silica-alumina-hafnia, silica-thoria, silica-alumina-thoria, silica-magnesia and alumina-alumi-

num fluoride. Alumina-molybdena and alumina-chromia catalysts are not desirable catalysts for this hydrogen transfer reaction. Using the catalyst from the above group the temperatures for the reaction will usually range from 300 to 500° C. with a preferred range of from 350 to 475° C. The pressure should be substantially atmospheric with enough differential to cause the desired flow. Thus the pressure should be from 1 to 2 atmospheres and preferably 1 to 1½ atmospheres. There is no free hydrogen consumed or produced in this hydrogen transfer reaction. Feed charge rates by weight of total charge stock per weight of catalyst per hour should be in the range of 0.1 to 10 and preferably in the range 0.5 to 5. These charge rates are indicated where a fixed bed catalyst is employed. If the hydrogen transfer reaction is to be effected in a fluid catalyst bed process, catalyst:oil ratios ranging from 1:1 to 30:1 by weight will usually be satisfactory. The preferred range is 5:1 to 15:1.

The invention is illustrated diagrammatically in the attached drawing. Reference is made to the drawing wherein in a naphthenic hydrocarbon, for example methylcyclohexane, is admitted through line 1 and an olefin, for example isobutylene, is admitted through line 2. These hydrocarbons are initially heated in heat-exchanger 3 and then heated to reaction temperature in heater 4 and passed into reaction 5 which contains a catalyst selected from the designated group. The effluent leaves the reactor through line 6, gives up heat to heat-exchanger 3 and is admitted an an intermediate tray of a conventional bubble cap fractionator 7. Unreacted hydrocarbons and low boiling aromatic hydrocarbons are passed overhead from fractionator 7 through line 11 and cooler 12 through condenser 13. Non-condensed gases are vented from condenser 13 from line 14. Condensed liquid hydrocarbons are passed from condenser 13 through line 15, heat-exchanger 3, heater 4 and returned to reactor 5 with the fresh hydrocarbon feed.

High boiling alkyl aromatics produced in the process, for example, 1,2,4-trimethylbenzene, are removed as a bottoms product from fractionator 7 through lines 8 and 10. If additional heat is required in fractionator 7 it is supplied in reboiler 9.

The following examples illustrate the advantages of this invention but are not intended to limit the invention.

EXAMPLE I

Four 10 minute runs reacting one part by weight of methylcyclohexane with 1.29 parts by weight of isobutene were made at 450° C. and atmospheric pressure using 100 ml. of synthetic silica-alumina bead-type catalyst crushed and sized to 40-60 mesh (U. S. Standard) with liquid hourly space velocities of 1.3. The liquid product was fractionated and the fractions were analyzed by the infra-red absorption method. The aromatic composition of the composite liquid product was as follows:

Table

	Percent
1,2,4-trimethylbenzene	8.1
p-Xylene	1.7
m-Xylene	2.1
o-Xylene	2.0
Toluene	5.0
Benzene	Trace

The total aromatics by the silica gel method was 25 percent.

EXAMPLE II

Various combinations of naphthenes and olefins were run over the catalyst of Example I and under conditions similar to those in Example I. The liquid products were not fractionated but were analyzed by the infra-red absorption method which showed a product distribution similar to that reported in Example I.

Reasonable variations and modifications are possible

within the scope of the disclosure and drawing of this invention, the essence of which is that a naphthene can be converted into an aromatic having a greater number of carbon atoms than the original naphthene by contacting the naphthene with an olefin, under hydrogen transfer conditions, and in the presence of a catalyst selected from the group consisting of alumina-aluminum fluoride, silica-boria, silica-alumina, silica magnesia, and the catalyst bases silica-alumina and silica activated by the oxides of the metals of groups 3-B and 4-B of the periodic table of elements as shown in Lange's Handbook of Chemistry, 1944.

We claim:

1. The process for producing aromatic hydrocarbons by converting naphthene hydrocarbons into aromatic hydrocarbons having a greater number of carbon atoms than the naphthene hydrocarbons which comprises reacting a hydrocarbon mixture comprising naphthenic hydrocarbons containing from 5 to 6 carbon atoms in the ring and a minimum of 6 carbon atoms in the molecule and olefinic hydrocarbons containing 3 to 6 carbon atoms as the sole reactants and having a naphthene to olefin ratio in the range 1:1 to 1:10, in the presence of a catalyst selected from the group consisting of alumina-aluminum fluoride, silica-boria, silica-alumina, silica-magnesia, and the catalyst bases silica-alumina and silica activated by oxides of the metals of groups 3-B and 4-B of the periodic table of elements at substantially atmospheric pressure, a temperature in the range 300 to 500° C., and a feed rate in the range of 0.1 to 10 by weight of feed catalyst per hour; separating the resulting hydrocarbon mixture in a distillation step; and recovering an aromatic hydrocarbon having a greater number of carbon atoms than said naphthenic hydrocarbon as a product of the process.
2. The process of claim 1 wherein the catalyst is silica-alumina.
3. The process of claim 1 wherein the catalyst is silica-alumina-zirconia.
4. The process of claim 1 wherein the catalyst is silica-zirconia.
5. The process of claim 1 wherein the catalyst is silica-titania.
6. The process of claim 1 wherein the catalyst is silica-thoria.
7. A process for producing aromatic hydrocarbons by converting naphthene hydrocarbons into aromatic hydrocarbons having a greater number of carbon atoms than the naphthene hydrocarbon which comprises reacting said naphthene hydrocarbon containing from 5 to 6 carbon atoms in the ring and a minimum of 6 carbon atoms in the molecule with an olefin hydrocarbon containing from 3 to 6 carbon atoms as the sole reactants in the presence of a solid catalyst selected from the group consisting of alumina-aluminum fluoride, silica-boria, silica-alumina, silica-magnesia, and the catalyst bases silica-alumina and silica activated by oxides of the metals of groups 3-B and 4-B of the periodic table of elements at substantially atmospheric pressure and at a temperature in the range 300 to 500° C.; separating the resulting mixture; and recovering aromatic hydrocarbons having a greater number of carbon atoms than the naphthene hydrocarbons as a product of the process.

8. A process for producing 1,2,4-trimethyl benzene which comprises reacting a naphthenic hydrocarbon having from 5-6 carbon atoms in the ring and a minimum of 6 carbon atoms in the molecule with an olefin having from 3-6 carbon atoms as the sole reactants in the presence of a catalyst selected from the group consisting of alumina-aluminum fluoride, silica-boria, silica-alumina, silica-magnesia, and the catalyst bases silica-alumina and silica activated by oxides of the metals of groups 3-B and 4-B of the periodic table of elements at substantially atmospheric pressure and a temperature in the range 350 to 475° C.; separating the resulting hydrocarbon mixture

in a distillation step; and recovering 1,2,4-trimethylbenzene as the kettle product of said distillation step.

9. A process for producing 1,2,4-trimethylbenzene which comprises contacting a hydrocarbon stream comprising a naphthenic hydrocarbon containing from 5 to 6 carbon atoms in the ring and a minimum of 6 carbon atoms in the molecule with a hydrocarbon stream comprising an olefinic hydrocarbon containing from 3 to 6 carbon atoms as the sole reactants and in a naphthene to olefin ratio in the range of 1:1 to 1:10 and with a catalyst selected from the group consisting of alumina-aluminum fluoride, silica-boria, silica-alumina, silica-magnesia and the catalyst bases silica-alumina and silica activated by oxides of the metals of groups 3-B and 4-B of the periodic table of elements, a pressure in the range of 1 to 2 atmospheres, at a temperature in the range 300 to 500° C., and a feed rate in the range 0.1 to 10 parts by weight of said hydrocarbons per part of catalyst per hour; separating the resulting hydrocarbon mixture in a distillation step; and recovering 1,2,4-trimethylbenzene as the kettle product of the distillation step as a product of the process.

10. The process of claim 8 wherein the catalyst is silica-alumina, the temperature is in the range 350 to 475° C., and the feed rate is in the range 0.5 to 5 parts by weight of hydrocarbon per part of catalyst per hour.

11. A process for producing 1,2,4-trimethylbenzene which comprises reacting methylcyclohexane with isobutene as the sole reactants in the presence of a catalyst selected from the group consisting of alumina-aluminum fluoride, silica-boria, silica-alumina, silica-magnesia, and the catalyst bases silica-alumina and silica activated by an oxide of the metals of groups 3-B and 4-B of the periodic table of elements at substantially atmospheric pressure and a temperature in the range 350-475° C.; separating the resulting hydrocarbon mixture in a distillation step; and recovering 1,2,4-trimethylbenzene as the kettle product of said distillation step.

12. A process for producing 1,2,4-trimethylbenzene which comprises reacting cyclohexane with isobutene as the sole reactants in the presence of a catalyst selected 40 from the group consisting of alumina-aluminum fluoride,

silica-boria, silica-alumina, silica-magnesia, and the catalyst bases silica-alumina and silica activated by an oxide of the metals of groups 3-B and 4-B of the periodic table of elements at substantially atmospheric pressure and a temperature in the range 350-475° C.; separating the resulting hydrocarbon mixture in a distillation step; and recovering 1,2,4-trimethylbenzene as the kettle product of said distillation step.

13. A process for producing 1,2,4-trimethylbenzene which comprises reacting methylcyclopentane with propylene as the sole reactants in the presence of a catalyst selected from the group consisting of alumina-aluminum fluoride, silica-boria, silica-alumina, silica-magnesia, and the catalyst bases silica-alumina and silica activated by an oxide of the metals of groups 3-B and 4-B of the periodic table of elements at substantially atmospheric pressure and a temperature in the range 350-475° C.; separating the resulting hydrocarbon mixture in a distillation step; and recovering 1,2,4-trimethylbenzene as the kettle product of said distillation step.

14. A process for producing 1,2,4-trimethylbenzene which comprises reacting methylcyclohexane with propylene as the sole reactants in the presence of a catalyst selected from the group consisting of alumina-aluminum fluoride, silica-boria, silica-alumina, silica-magnesia, and the catalyst bases silica-alumina and silica activated by an oxide of the metals of groups 3-B and 4-B of the periodic table of elements at substantially atmospheric pressure and a temperature in the range 350-475° C.; separating the resulting hydrocarbon mixture in a distillation step; and recovering 1,2,4-trimethylbenzene as the kettle product of said distillation step.
